UNITED STATES PATENT OFFICE.

EARL R. PERSON, OF LEOMINSTER, MASSACHUSETTS, ASSIGNEE TO VISCOLOID COMPANY, A CORPORATION OF MASSACHUSETTS.

MACHINE FOR FEEDING AND POINTING HAIRPIN BLANKS AND THE LIKE.

Application filed June 9, 1920. Serial No. 387,567.

To all whom it may concern:

Be it known that I, EARL R. PERSON, a citizen of the United States, residing at Leominster, in the county of Worcester and

5 State of Massachusetts, have invented a new and useful Machine for Feeding and Pointing Hairpin Blanks and the like, of which the following is a specification.

This invention, although capable of general use, is especially designed for feeding of celluloid hair-pin blanks in straight cylindrical form to a hair pin bending machine, centering them with respect thereto, and pointing their ends.

15 The principal objects of the invention are to provide simple means for taking the blanks one at a time from a hopper in which they are located and supplying them to a carrier, to provide a carrier with an intermittent motion, and with means for grasping the blanks and delivering them to a centering and pointing device; and to provide an effective and mechanical pointing device for simultaneously pointing both ends of the 20 blank and holding them in proper position to be delivered into the hair pin bending machine or other device for further treatment. The invention also involves improvements in the details of construction of these 25 various parts and in the way in which they are combined with each other.

30 Reference is to be had to the accompanying drawings in which—

Fig. 1 is a side view of a machine constructed in accordance with this invention connected with a hair pin bending machine to which it delivers its product;

Figs. 2 and 3 are opposite end views of the same, and

40 Fig. 4 is an enlarged sectional view on the line 4—4 of Fig. 1.

The invention is shown as mounted on a frame or base 10 which is also connected with a support 11 for the hair pin bending machine 12. The details of the hair pin bending machine will not be described as the one shown is described in full in my Patent No. 1,330,450 granted Feb. 10, 1920. It is provided with a pulley 13 on a shaft 14 which receives power from a counter shaft

above or in any other desired way, and by belt drives a pulley 15 on the transverse main shaft 16 of the machine which is the subject of this invention.

The main shaft 16 is provided with a 55 worm 17 operating a worm gear 18 on a longitudinal shaft 19 on which is a cam 20, preferably a double cam. The rotation of this cam depresses a roll 21 on a swinging lever 22 which by means of a link 23 operates a lever 24 pivoted on the frame 10 to lift a feed plate 25 pivoted to its end. The weight of this plate can be employed to hold the roll 21 up in contact with the cam 20 if desired. 60

This plate 25 is provided with a concave end at 26 large enough to hold one hair pin blank and no more and this reciprocates up and down in a hopper 27, the bottom walls 28 of which converge toward the center so 70 that the hair pin blanks or other cylinders will roll down to the bottom of it and one of them will be lifted practically every time the plate 25 rises in the hopper. This constitutes the means of feeding one blank at a 75 time up out of the hopper until the last one is discharged from it. This concave top 26 is so narrow that there is no possibility of feeding two blanks at once.

Also mounted on the shaft 16 there is a 80 pinion, not shown, which meshes with a gear 31 on a shaft 32 provided with another cam 33, preferably a double cam, which operates a roll 34 on a spring-pressed lever 35 pivoted at 36. This lever is provided with a link 37 at its free end to which is connected a spring-pressed ratchet tooth 38 mounted in a holder 39 at its end. This engages a ratchet wheel 40 and every time either end of the cam 33 depresses the lever 35 the ratchet tooth 38 will engage one of the teeth of the wheel 40 and advance this wheel the length of the space between two adjacent teeth. This gives the shaft 41 on which the ratchet wheel 40 is fixed an intermittent rotary motion in the direction of the arrow. 90

On this shaft 41 is mounted a rotary carrier 42. This is provided with a plurality of pairs of spring gripping devices 43 equal in number of sets to the teeth of the wheel! 100

40 and each consisting of two pairs of spring fingers which are near enough together to grasp a hair pin blank between them and hold it and are spread apart at their ends to 5 permit it to receive them.

The intermittent rotation of the carrier 42 presents the blanks held by the grip fingers 43 periodically into a position in which they can be acted on by the pointing mechanism. 10 Mounted on the shaft 19 there are two cams 44 each operating a roller 45, each of which is mounted on a lever 46 pivoted at 47 between its ends and pivotally connected at its upper end with a holder 48. On a stationary projection 49 on the frame 10 is pivoted a link 50, the upper end of which is also pivotally connected with the holder 48. The holder 48 will move in a slightly arcuate direction out and in. This holder is 15 provided with a pulley 51 which rotates a cutter shaft 52 on which is mounted a cylindrical cutter 53 rotating on an inclined axis. It has spur gear teeth 55 on one side meshing with an internal gear 65 on the holder 48. This cutter rotates around the center with a planetary motion so as to sharpen or cut a point on a hair pin blank when it is centered in a conical center 54 with which this holder is provided. This 20 mechanism is duplicated on the other side and it will be seen that the operation involves the presentation of the hair pin blank or cylindrical rod by means of the carrier 42 directly in line with the centers 54, at 25 which time the carrier stops. Then the cams 44 actuate the parts just described to bring up the centers 54 and accurately center the blank at both ends, and then to move further in so that the blank will be 30 sharpened at both ends. Then the cutters are automatically withdrawn and the carrier 42 takes another step forward, after 35 which the blank is discharged in the following way.

40 The cam 20 operates a roller 56 on a lever 57 connected with a link 58 that oscillates an arm 59 on a shaft 60 supported by the frame 10 and which is provided with ejectors 61 in the form of two or more hooks. These 45 periodically engage the blanks held by the springs 43 and detach them, allowing them to fall from these hooks and drop on an inclined surface 62 which delivers them into a hopper 63 of the hair pin bending machine 12.

50 It will be understood of course that the form of the hair pin bending or making machine to which the blanks are delivered is immaterial, and I will not describe the same in detail except to say that in the form 55 shown the blanks are fed out of the hopper 63 and rolled along the table 64 until they come against stops not shown. Then a plunger moves forward to bend the pins and another plunger moves down to shape them, 60 but any other mechanism can be employed 65

at this point and the machine which is the subject of this invention can be used by itself.

Although I have illustrated and described only a single form of the invention I am 70 aware of the fact that modifications can be made therein by any person skilled in the art without departing from the scope of the invention as expressed in the claims.

Therefore I do not wish to be limited to 75 all the details of construction herein shown and described, but what I claim is:

1. In a machine for pointing the ends of rod-like blanks, the combination of a pair of centers for supporting the ends of said 80 blanks, a holder on each side of the machine, said holders being mounted to swing, substantially parallel motion connections for swinging them forward and back, and a cutter behind each center in each holder for engaging the surfaces of the end of the blank and simultaneously pointing both its ends. 85

2. In a machine for pointing the ends of rod-like blanks, the combination of a pair of centers for supporting the ends of said 90 blanks, a cutter behind each center for engaging and cutting the end of the blank, two holders, a shaft having bearings on each holder for supporting one of said centers, and cutters and operating the cutter, a lever 95 supporting one end of a holder for moving it back and forth, a link connection supporting the other end always at substantially the same level as the end supported by the lever, and means for moving said levers toward each other to center the blank and point both its ends. 100

3. In a machine for pointing the end of a rod-like blank, the combination of a center for supporting the end of one of said blanks, 105 a cutter behind the center for engaging and cutting the end of the blank, a movable holder, a shaft on the holder supporting the center and cutter and rotating the cutter, a lever pivotally connected with the forward 110 end of the holder, positive means for operating the lever to swing the holder inwardly to operative position, and a link pivoted to the holder at the same level as the lever is, and pivoted to a stationary part of the machine at substantially the same level as the pivotal support for the lever for moving said center and cutter forward to center the blank and point its ends. 115

4. In a machine for pointing the end of a rod-like blank, the combination of a center for supporting the end of said blank, a cutter behind the center for engaging and cutting the end of the blank, a lever for supporting said center and cutter and moving 120 them into a position to center the blank and point its end, and a link for ensuring a parallel motion for the center. 125

5. In a machine of the character described, the combination of a rotary carrier having 130

a series of pairs of radial flat spring fingers each fixedly mounted thereon adapted to engage the blanks to be operated upon and clasp them by their own resiliency at a distance from the carrier, means for rotating said carrier by a step-to-step motion, a hopper below the carrier for receiving the blanks, means for positively moving a single blank up from the hopper in a radial direc-

tion into the space between a pair of said fingers when the carrier is in stationary position with said pairs of fingers extending downwardly, and means for stripping the blanks from the fingers.

In testimony whereof I have hereunto affixed my signature.

EARL R. PERSON.
